(57) **CLAIM**

The ornamental design for a sensor headlamp, as shown and described.

DESCRIPTION

FIG. 1 is a front and top perspective view of a sensor headlamp showing my new design.

FIG. 2 is a front view of a sensor headlamp.

FIG. 3 is a rear view of a sensor headlamp.

FIG. 4 is a left side view of a sensor headlamp.

FIG. 5 is a right side view of a sensor headlamp.

FIG. 6 is a top view of a sensor headlamp; and,

FIG. 7 is a bottom view of a sensor headlamp.

Any shading and cross-hatching are not features of the design but are utilized to illustrate the surface contours of the sensor headlamp in the drawings.

The broken lines in the drawings depict portions of the sensor headlamp that form no part of the claimed design.
